ATTORNEYS,

UNITED STATES PATENT OFFICE.

WILLIAM WHITE, OF NEW YORK, N. Y., ASSIGNOR TO CLARENCE WHITMAN & CO., OF SAME PLACE.

DESIGN FOR A BEDSPREAD.

SPECIFICATION forming part of Design No. 23,489, dated July 24, 1894.

Application filed June 28, 1894. Serial No. 515,791. Term of patent 3½ years.

To all whom it may concern:

Be it known that I, WILLIAM WHITE, a citizen of the United States, residing in the city, county, and State of New York, have invented and produced a new and original Design for Bedspreads, of which the following is a specification, reference being had to the accompanying drawing, which represents a face view of a portion of a bedspread embodying my design, part only being shown in detail, the remainder being shown in outline.

The leading feature of my design is a bedspread ornamented with a series of rosettes of essentially the configuration shown in the accompanying drawing with a border or edging presenting a lattice-work effect, portions of the field of the spread being filled in with configurations representing a lattice-work effect.

In the drawing, *a* is a lattice-work figure bordered with conventionalized leaves *b b* and intertwined serpentine scroll *j*; *c* an adjacent

serpentine scroll, *d* a lattice-work configuration or effect adjacent to the scroll *c*. Adjoining the lattice-work *d* are rosettes formed of conventionalized leaves *e e e* with the adjacent scrolls *f* and the intertwined serpentine scroll *l*. Adjacent to the rosettes and scrolls is a rosette composed of the central lattice-work configuration or effect *g* with the surrounding conventionalized leaves *h*, and the intertwined serpentine scroll *k*. *A* is a border or edging presenting a lattice-work effect.

The field of the spread inside the border is decorated with small polygons presenting a mottled effect.

What I claim is—

The design for a bed-spread, substantially as shown and described.

WILLIAM WHITE.
